Registration No. 10,310, Mar 10, 1870.

Issue date 9-1890.

United States Patent Office.

WILLIAM R. OLMSTED, OF FAYETTE, NEW YORK.

Design No. 4,169, dated June 21, 1870.

DESIGN FOR BREAST-COLLAR FOR HARNESS.

The Schedule referred to in these Letters Patent and making part of the same.

To all whom it may concern:

Be it known that I, WILLIAM R. OLMSTED, of Fayette, in the county of Seneca and State of New York, have invented or produced a certain new and original Design for a Breast-Collar for a Harness, of which the following is a specification.

Nature of Invention.

This design consists in constructing breast-collar or plate of a harness as hereinafter described.

General Description.

In the drawing—

Figure 1 is a side view, and

Figure 2, a front view.

In the drawing—

A is the front portion, and

B the side portions.

These portions are continuous of each other, or are of one unbroken line.

From each side of the central point of the part A there is a gentle curve to the parts *a a*, thus leaving a depression at the center.

b represents ornamental and strengthening stitching, which extends along the front face of the collar.

The ordinary traces and neck-straps are secured to the collar.

Having thus described my invention,

What I claim as new, and desire to secure by Letters Patent, is—

The design for a breast-collar, as herein described and represented.

In witness whereof I have hereunto signed my name in the presence of two subscribing witnesses.

WM. R. OLMSTED.

Witnesses:

R. F. OSGOOD,

GEO. W. MIATT.
